[57] CLAIM

The ornamental design for a calliper as shown and described.

DESCRIPTION

FIG. 1 is a front and left side perspective view of a calliper showing my new design;

FIG. 2 is a rear and right side perspective view;

FIG. 3 is a partial rear, left side and top perspective view;

FIG. 4 is a partial front, left side and bottom perspective view;

FIG. 5 is a partial front, right side and top perspective view;

FIG. 6 is a partial front, left side and bottom perspective view, shown with the armatures in an open condition of use; and,

FIG. 7 is a partial front, right side and bottom perspective view thereof, shown with the armatures in an open condition of use.

The end portion of the calliper's handle has been eliminated for ease of illustration in FIGS. 3-7.

FIG. 1

FIG. 2

FIG. 3
